Application September 25, 1936, Serial No. 102,448

2 Claims. (Cl. 30—212)

This invention relates to tools, and more particularly to multiple strand cutters.

In apparatus employing a plurality of predeterminedly spaced substantially parallel strands or wires; for example, in the manufacture of telephone cross-bar switches, there are assembled a plurality of closely arranged sets of horizontal straps or wires, each set comprising, in one arrangement, six parallel similarly spaced wires, 10 each soldered to one contact spring of a plurality of sets thereof spaced along their lengths, the points of soldering of the wires to the contact springs of each set being progressively offset to provide greater clearance between the points of soldering. After the soldering operation, the projecting ends of the wires extending from the offset soldered points of the end sets of contact springs are trimmed or cut off adjacent the soldered points.

An object of this invention is to provide a tool capable of efficaciously severing with a predetermined uniformity a plurality of substantially parallel predeterminedly spaced strands simultaneously.

In accordance with the general features of the invention, there is provided in one embodiment thereof for use in trimming the ends of telephone cross-bar switch straps or wires, above described, a pair of interpivoted handles to one of which is rigidly fixed a forwardly extending cutting blade. Disposed laterally of the pivotal point of the handles is a second forwardly extending cutting blade which is pivoted to the other handle by an elongated slot and pin connection. A dovetail extension on one blade riding in a complementary recess formed in the other member cause the blades to move in a rectilinear path one upon the other upon a relative sliding movement being effected therebetween when the handles are pressed toward each other. The cutting blades are each formed with a plurality of similarly spaced parallel strand or wire receiving notches each having a cooperating shearing edge, the notches extending diagonally and transversely of the blades to correspond to the offset points where each wire is to be trimmed.

Other objects and advantages of this invention will more fully appear from the following detailed description, taken in connection with the accompanying drawing, wherein

Fig. 1 is a side view, partly in section, of a wire cutter embodying the features of this invention;

Fig. 2 is a bottom plan view showing, in broken lines, a plurality of wires positioned in the wire receiving notches ready to be severed;

Figs. 3 and 4 are vertical sections taken on the lines 3—3 and 4—4 of Fig. 1, and

Fig. 5 is a fragmentary side view similar to Fig. 1, showing another embodiment of the invention.

Referring to the drawing, the wire cutter as shown comprises a pair of hollow handles 10 and 11 bifurcated at their inner ends. Fixed between the furcations of the handle 10 is an irregularly shaped member 12 having integral therewith a forwardly extending cutting blade 13 (Figs. 2, 10 and 3). A bifurcated member 14 is fixed between the furcations of the handle 11, the furcations of the member 14 extending upwardly, with the member 12 pivoted therebetween, as indicated at 15. Operatively connected to the member 14 between the furcations thereof, is a forwardly extending cutting blade 18, having formed on its inner surface, as viewed in Fig. 3, a dovetail extension 19 which is fitted to slide within a complementary recess 20 formed in the adjacent 20 abutting surface of the blade 13 of the handle 10 (Fig. 3). An elongated vertical slot 21 in the blade 18 with a pin 22 (Figs. 1 and 4) carried by the furcations of the member 14 passing through the slot provides a pivotal operative connection 25 between the member 14 and the blade 18. The pivot point is disposed at a distance from the pivot 15 relatively short as compared with the length of the handles, thus providing a multiplying action for sliding the cutting blades 13 and 18 relative to each other, the blades being caused to move in a rectilinear path without undue friction one upon the other by means of the dovetail connection when the handles are pressed toward each other. The opposite longitudinal side faces 30 of the blades 13 and 18 are beveled inwardly along their lower portions to provide narrow bottom work engaging faces in which are formed a plurality of, in the present embodiment six, similarly spaced parallel strand or wire receiving notches 35 40 45 50 55 25.

The wire receiving notches 25, as clearly shown in Fig. 2, extend diagonally across the width of the blades and not at right angles thereto. This diagonal arrangement of the parallel notches, 45 when wires 27 (Fig. 2) to be severed are positioned therein and extending parallel thereto are cut, will result in the points of cutting being progressively offset along a predetermined diagonal line. Also, since the parallel diagonally arranged notches are formed with a predetermined width suitable only to receive freely the wires to be cut, but without excessive play, the wire cutter can only be positioned on the wires by the operator in a manner which will result in the points 55

of cutting being offset along a predetermined diagonal line. Furthermore, in the use of the wire cutter, the diagonal arrangement of the wire receiving notches 25 makes it possible for the 5 operator to more efficiently position the wires 27 (Fig. 2) in the notches as the wire cutter is moved into operative position relative to the wires, for the operation may be more clearly observed, since the operator's hand may be to one 10 side of the points where the notches 25 receive the wires 27, which may be directly in front of him.

The handles 10 and 11 are normally urged apart, as shown in Fig. 1, by a leaf spring 28 15 having one end fixed to the handle 10 and its opposite end entered in a slot provided in the member 14. A stop pin 29 fixed to the member 12, the latter being rigid with the handle 10, limits the separating movement of the handles 20 under the action of the spring 28, the stop pin forming an abutment for the member 14 carried by the handle 11. In the normal position of the handles 10 and 11, as shown in Fig. 1, the series 25 of wire receiving notches 25 formed in each of the cutting blades 13 and 18 are in alignment, as clearly shown in Fig. 2. When the handles are pressed together to perform the severing operation, the movement thereof is limited by the member 14 of the handle 11 engaging the member 30 12 of the handle 10 at the points indicated at 30.

In use for trimming the ends of telephone cross-bar switch straps or wires, hereinbefore described, the wire cutter is held by the operator with the handles 10 and 11 in their normal or 35 open positions, as described hereinbefore, and is then moved toward and at an angle of approximately 45 degrees to the longitudinal axes of the spaced parallel wires 27, it being assumed that the diagonal line of the soldered points indicated at 32 (Fig. 2) of the wires 27 to their contact springs (not shown) of the cross-bar switch has this angle, into position over the wires with the notches 25 in alignment therewith, the cutter then being lowered to enter the wires in the 40 notches. Upon thus being positioned, the operator presses the handle 11 upwardly toward the handle 10, which movement causes the cutting blade 18 to move toward the right as viewed in Figs. 1 and 2, and all the wires are cut simultaneously between shearing faces 33 of the blades 13 and 18 (Figs. 2 and 3), leaving an equal small 45 length of wire extending from each soldered point. Upon the operator releasing the handle 11, the spring 28 returns the handle and the cutting blade 18 to their normal positions.

50 It will be noted that the handles 10 and 11 are so shaped and so related to the blades that the upper handle 10 will normally lie in the hollow of the operator's hand while the pivotally connected handle 11 engages the operator's finger. With this arrangement, it is very easy during operation for the operator to maintain the blades in the plane of the series of wires being cut. The work of closing the handles is almost wholly accomplished by movement of the fingers and since 55 the blades are rigidly held in an extended position from the upper handle, there is little or no tendency for the blades to be swung out of engagement with the wires at either extremity of the series of contact springs.

70 In Fig. 5, there is shown fragmentarily an embodiment of the wire cutter of this invention, which is similar to that described above except that wire receiving notches 25 with shearing edges

are formed upon the upper edges of the cutting blades 13 and 18 as well as upon the lower edges thereof for efficiently performing the above described wire trimming operation upon a plurality of aligned spaced sets of wires 27, wherein one 5 severing operation may be effected and then by merely moving the wire cutter one way or the other without withdrawing it from between the sets of wires the second set of wires may be trimmed. This form of the invention is also 10 useful where it is inconvenient to insert the tool at the upper side of the wires to be severed.

Although in the wire cutter illustrated and described the wire receiving notches, as viewed in Figs. 1 and 2, extend downwardly from left to right and at a particular angle it will be obvious 15 that they may extend in the opposite direction and at a different angle.

While the invention has been described with particular reference to the simultaneous severing 20 of a plurality of wires as arranged in a telephone cross-bar switch, it is not limited to such use and it will be understood that the invention is capable of other applications and that modifications can be made without departing from the 25 spirit and scope of the appended claims.

What is claimed is:

1. A tool for simultaneously cutting a plurality of parallel predeterminedly spaced fixed wires with the points of cutting being progressively offset along the length of the wires comprising a member having a plurality of wire receiving notches having cutting edges, an actuating member pivotally connected thereto, a second member having a plurality of wire receiving notches having cutting edges cooperating with the notches and cutting edges of said first member, said second member being pivotally connected to said actuating member, said notches extending diagonally and transversely of the members at a predetermined angle, the notches in each member having a spacing similar to that of the wires to be cut, one of said notched members having a dovetail extension engaging in a complementary recess in the other notched member to cause said latter member to move in a predetermined path by said actuating member, and means including a resilient element for maintaining said second notched member in a normal position with its notches aligned with the notches of said first member for receiving wires to be cut. 30

2. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 35

3. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 40

4. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 45

5. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 50

6. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 55

7. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 60

8. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 65

9. A tool for simultaneously cutting a plurality of parallel predeterminedly spaced fixed wires with the points of cutting being progressively offset along the length of the wires comprising a member having a plurality of wire receiving notches having cutting edges, an actuating member, means for operatively connecting said actuating member to said notched member, a second member having a plurality of wire receiving notches having cutting edges cooperating with the notches and cutting edges of said first member, and means for pivotally connecting said second member to said actuating member, said notches extending diagonally and transversely of the members at a predetermined angle, the notches in each member having a spacing similar to that of the wires to be cut, said notched members having cooperating surfaces for causing said latter notched member to move in a predetermined path by said actuating member. 70
